UNITED STATES PATENT OFFICE.

ABRALOM R. GUILDER, OF MINNEAPOLIS, MINNESOTA.

MIDDLES-PURIFIER.

SPECIFICATION forming part of Letters Patent No. 225,218, dated March 9, 1880.

Application filed December 18, 1879.

To all whom it may concern:

Be it known that I, ABSALOM R. GUILDER, of Minneapolis, in the county of Hennepin, in the State of Minnesota, have made certain Improvements in Middlings-Purifiers, of which the following is a specification.

The object of this invention is to so improve the machines heretofore used in purifying middlings that a single passing of the middlings through the improved machine will do and accomplish what required several operations in other machines, and also to prevent explosions by reason of the igniting of the fine floating dust in the mill; and the invention consists in the special constructions and combinations of parts that accomplish the object, as will fully hereinafter be described.

In the drawings, Figure 1 represents a longitudinal sectional view of the machine on line $y-y$ of Fig. 2, Sheet 2, and Fig. 3, Sheet 3. Fig. 2, Sheet 2, is an upright view of one end of the machine. Fig. 3, Sheet 3, is an upright view of the opposite end of the machine. Fig. 4, Sheet 3, is a plan view of transverse brush and devices to give it motion; and Fig. 5, Sheet 1, shows enlarged view of details of parts.

10 A represents the usual frame to support the operating parts of the machine.

15 A' is a transverse shaft driven by any convenient power by a belt around pulley a. Shaft A' is also the shaft for exhaust-fan case A'''.

B is the feed-hopper into which the middlings to be purified are fed. B' is the feed-35 roller at the bottom of hopper B.

b is a sliding valve to control the amount of middlings fed into the machine, and it is held in the desired position by holding-screws b' through slots b'' in valve b.

20 C is a revolving cylinder-brush on transverse shaft C', caused to revolve by any proper means from shaft A''.

C'' is a segmental jacket around one-half (more or less) of the periphery of the revolving brush C. This jacket is of sheet metal, corrugated on its inner surface, or roughened,

45 so that as the grains of middlings are forced against the rough surface by the brush all the linty or fluffy and light adhering particles 50 will be detached from the middlings.

c is a concave block, inclined on its top side to direct the middlings to the brush, with a

right-angled bottom to stop the brush from carrying any material up or above its bottom edge.

55 c' is an inclined guide-board, to give direction on the opposite side of the feed-hopper to the middlings, and insure the delivery of the middlings to be carried forward by the brush.

c'' is a wedge-shaped contracting bar bearing on the under side of the yielding jacket C'', to cause the jacket to be brought into closer contact with the revolving brush when necessary, and is operated by the rods c³, and retained in position by the screw-nuts c'. By 60 this construction the jacket C'' becomes either expanding or contracting in its action, while the brush is non-expanding; but the same result would be effected by having the brush expanding or contracting in its diameter while 70 the jacket is fixed in its diameter.

D is a wind-valve hinged at its bottom edge, and regulated in its adjustment by rod d and screw-nut d', to admit a greater or less amount of air through aperture D' in the casing of the 75 machine. It also deflects the inflowing air-current in a proper direction.

E is an endless carrier, with its carrier-troughs E' attached to chains e, that pass over sprocket or other wheels e' on transverse shafts 80 e'' e'' in dust-chamber E'', and may receive its motion from either of shafts e'' by any proper means from the main shaft A'.

F is a brush attached to the endless carrier-chains e, and travels with the chains around 85 the shaft e'' and in contact with a removable dust-cloth, F', that is situated directly over the carrier and serves the purpose of keeping the meshes in cloth F' open to allow the free passage of air, and any light fine dust to pass 90 through the cloth into the fan-case, and thence to be forced out through exit-opening X of the air-tube to fan-case A''', and outside of the mill-building. This fine dust so discharged is by this construction prevented from mingling with the heated air in the mill, and will prevent the liability of an explosion such as frequently occurs to the destruction of the 95 itself.

100 f is an inside inclined hopper directly under the delivery end of the endless carrier, and conducts whatever passes off the carrier outside of the machine, or outside of the building,

through opening r' in the casing of the machine. Opening r' , for safety, is inclosed on its outside by flap-valve r'' .

G G are the longitudinal reciprocating side pieces of the shaking and reciprocating bolt, having cross-girts G' at one end and as many intermediate ones as may be necessary for strength.

g is the bolt-cloth, secured to the under side of the frame G G', and may be in several different numbers of fineness of mesh, so as to grade the middlings as to fineness and quality, as desired. The bolt-frame is suspended on hangers g', near to the four corners of the frame.

G'' is a cross-piece of the frame at the receiving end of the reciprocating bolt, and extending outside of the case far enough to form the bottom of hopper H, that receives the middlings from the disintegrating-brush C, and delivers them upon the bolt-cloth g of the shaker.

h h are diagonal or cross rods secured at one end to the sides of the shaker, and the other end passing through the casing, where it is regulated by an adjusting-nut, h', and, by contracting the rod in its length, brings the frame over toward that side of the casing, hence will throw the reciprocations of the shaker-frame out of a direction parallel with the center of the machine and change the direction of the middlings on the bolt-cloth.

I is a transverse revolving shaft, getting its motion from shaft A'' by belt and pulleys, or any other convenient means, and has two eccentricities fast upon it near the sides of the case, which revolve in boxes in stirrups i' i'', that are secured to the sides of the shaker-frame, and by which the bolt or shaker is reciprocated.

J J are two revolving longitudinal shafts, made to revolve by any convenient means from the driving-shaft A'', and have their journal-bearings in transverse bridge-trees, and have sprocket or toothed wheels j near each end and fast thereon.

J' J' are transverse and adjustable bridge-trees, in which are the journal-boxes of the shafts J. These bridge-trees are adjustable up or down, for the purpose of adjusting the brush, that wipes the under side of the bolt-cloth as the brushes wear off, through the means of the slcts. j' j'' and holding-screws j'.

K is a brush placed longitudinally under the bolt-cloth g, the bristles of which are fast in the stock K'.

k k are supports to the brush K, extending from and around the shafts J, so that the said shafts revolve within them at each end of the supports, and upon which supports the brush-stock freely slides in its passage over them.

L is a transverse guide-stock attached to one of the supports k, and has secured upon its upper edge a corrugated guide-plate, l, that goes between two friction guide-rollers, k', on downwardly-projecting studs k'' on the under side of brush-stock K'.

O O are endless chains that go around

sprocket-wheels j on shafts J, and travel in a transverse direction under the bolt-cloth g, and to which chains the brush-stock K is attached by means of the staples or hooks o, so that as the chains travel in one direction they carry the brush-stock with them in a transverse direction across the entire width of the bolt-cloth, and while it so travels the corrugated or bent guide-plate l and friction guide-rollers k' cause the brush to have a longitudinal or endwise motion of several reciprocations while it is in contact with and sweeping across the bolt-cloth, thus giving to the brush a motion in two directions while in contact with the bolt-cloth, which is more effective in clearing the meshes of the bolt-cloth from all adhering substances.

Operation: The middlings are fed into the hopper B, and the feed regulated by the feed-roller B'; thence the middlings gravitate to the revolving brush C, and are carried around in contact with the roughened surface of the jacket C'', where the grains of middlings are scoured between the brush and the rough surface of the inner side of the jacket, which scours off all adhering linty and useless particles from the middlings, and, as the scoured middlings and the particles detached therefrom fall out of contact with the jacket and brush, they come in direct contact with an inflowing current of air through an opening at the bottom of the hopper, which current of air carries upward all the light coarse material and the fine linty or fibrous substance and dust, through the dust-space, against a dust-cloth at the upper or top part of the machine by the exhaust-fan A'', the finest dust passing through the cloth to the fan, and thence out of the machine, while the coarser and heavier particles fall upon the troughs on the endless carrier, to be carried to the opposite side of the machine, to be passed outside thereof, and at the same time a brush traveling with the endless carrier sweeps off any adhering substance or particles from the dust-cloth above the endless carrier, and serves to keep the meshes of the dust-cloth open, so as to admit of a free circulation of air up through the machine to the exhaust-fan.

The scoured middlings and particles too heavy to be carried off by the air-current fall into hopper H at one end of the reciprocating shaker or bolt, thence onto the bolt-cloth, where they are subject to the quick reciprocations of the shaker, the middlings falling through the bolt-cloth, that is graded in its meshes, down into the conveying device, to be disposed of as desired, while the coarser particles that cannot go through the cloth are passed off the tail of the bolt and conveyed away, to be disposed of separate from the middlings.

All the time that the middlings are upon the bolt a current of air is caused to go through the openings between the overlapping slats near the bottom of the machine by the exhaust-fan A'', which assists in taking from the

middlings on the bolt any fine light particles that escaped the first winding of the middlings, and carries such light substance up to be discharged from the machine by the endless carrier E, and disposed of in the manner before described.

Having thus described my invention, what I claim is—

1. In a middlings-purifier, the combination of the revolving brush C, the yielding jacket C'', having its inner surface corrugated or roughened, and inclined and concave feed-block c, constructed and operating as described.
2. In a middlings-purifier, the combination of the yielding jacket C'', having a corrugated or roughened inside surface, the contracting bar c', rods c', and nuts c' with the revolving brush C, constructed and operating substantially as described.
3. In a machine for purifying middlings, the combination of the revolving scouring-brush C, yielding jacket C'', and endless carrier E, having carrier-troughs E', and exhaust-fan A'', as and for the purposes specified.
4. The traveling brush F, carrier-troughs E', and dust-cloth F', in combination with the exhaust-fan A'', substantially as and for the purposes described.

5. The combination of the reciprocating bolt G g and transversely-moving brush K, having a longitudinal reciprocating motion, substantially as and for the purpose described. 30

6. The combination of the corrugated guide-plate l on cross-bar L with the transversely-traveling brush K, having guide-rollers k' k', 35 as and for the purposes described.

7. The combination of the reciprocating bolt G g, the transversely-traveling and longitudinally-moving brush K, and adjustable bridge-trees J', as and for the purpose described. 40

8. The combination of the diagonal cross-rods h with the reciprocating shaker or bolt G g, as and for the purposes described.

9. The combination, in a machine for purifying middlings, of the revolving brush C, the 45 corrugated or roughened yielding jacket C'', the dust-cloth F', traveling brush F, the reciprocating bolt G g, and transverse longitudinally-reciprocating brush K, their operating devices, and exhaust-fan A'', constructed and operating as and for the purposes substantially as described. 50
